UNITED STATES PATENT OFFICE.

MADISON D. SHIPMAN, OF DE KALB, ILLINOIS, AND EMMET P. BUNYEA, OF WASHINGTON, DISTRICT OF COLUMBIA; SAID BUNYEA ASSIGNOR TO SAID SHIPMAN.

GLOVE-FASTENING.

SPECIFICATION forming part of Letters Patent No. 663,521, dated December 11, 1900.

Application filed April 28, 1897. Serial No. 634,254. (No model.)

To all whom it may concern:

Be it known that we, MADISON D. SHIPMAN, of De Kalb, county of De Kalb, Illinois, and EMMET P. BUNYEA, of Washington, District 5 of Columbia, citizens of the United States, have invented certain new and useful Improvements in Glove-Fasteners; and we do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

Our invention relates to the head or stud catch members of glove fasteners and studs and to the means of attaching the same to the glove or material; and the objects are to provide a button of this character which shall be 20 simple in construction, of comparatively few parts not easily strained or distorted in use, and to improve the means of securing or attaching such fasteners to the material. We 25 attain these objects by means of the construction shown in the accompanying drawings, and hereinafter more particularly described and claimed.

In said drawings, Figure 1 is a vertical sectional view of the head or socket member, showing the same attached to the material. Fig. 2 is a similar view of the parts shown in Fig. 1 previous to their attachment to the material and showing in dotted lines the tools 30 in one position during the process of attaching the same to the material. Fig. 3 is a vertical sectional view of a slightly-modified form of socket member, showing a catch and a closed cap or cover therefor secured to the material. Fig. 4 is a similar view of the parts 35 shown in Fig. 3 previous to the assembling of the outer cap *b* and the fastening-eyelet *B* and their attachment to the material. Fig. 5 is a vertical section through the stud member and its attaching-rivet, showing said parts 40 attached to the material and also illustrating one form which the rivet may assume in the setting or clenching operation. Fig. 6 is a vertical section through an attaching-rivet of 45 similar form and having its flange covered by 50

a coating of celluloid or other plastic material. Fig. 7 is a vertical section of the rivet, taken at right angles to the view in Fig. 6, with the coating omitted. Fig. 8 is a perspective view of the rivet. 55

As shown in Fig. 1, the socket member consists of two parts, the stud-catch *A* and the combined cap and fastening-eyelet *B*. The stud-catch shown in this figure of the drawings has a hollow dome-shaped shell or upper 60 portion *a* and a base-flange *b*. At the base of the hollow dome-shaped shell the catch is contracted to form a recess *c*, and the flange is curved upward from this recess to near its outer edge. This recess *c* is for the purpose 65 of serving as an anvil or upsetting-surface for the end of the fastener *B*. In attaching these parts to the material the stud-catch *A* is placed upon the protruding end of a tool or mandrel, and the cap, as *B*, is supported upon 70 the opposite side of the material in a suitable tool held in alinement with the catch. When the two parts are forced together, with the material between them, the end of the eyelet *d* is curled or upset either outwardly or inwardly 75 within the recess *c*, surrounding the base of the dome. When a spring-catch is to be used, the tool upon which the catch is supported is of sufficient size to open and hold during the setting operation the slit to just the required 80 degree to admit the coacting stud member with which this catch is to be used. The upset or curled edge *d* of the fastening-tube serves as a guard to limit the expansion of the stud-catch opening and to prevent injury 85 or distortion to the catching edge of the stud-catch. As shown in Figs. 3 and 4, the stud-catch is hollow and has an open upper end *a'* of substantially the same size as the stud-catch opening *b'*. 90

A supplemental cap or cover *b*² is shown in Figs. 3 and 4 to cover the button in Fig. 4 before assembling the parts. The stud-catch shown in said Figs. 3 and 4 is secured to the material in substantially the same manner as 95 that shown in Figs. 1 and 2, with this difference, however, that the end of the mandrel projects through the opening *a'* at the upper end of the catch and centers the catch. Substantially the same form of eyelet *B* is used for 100

securing the catch shown in Figs. 1 and 3, the end of said eyelet being shown as curled inward in said Fig. 3 within recess c in the stud-catch instead of outward, as shown in Fig. 1. It will be noticed that this stud-catch, formed as shown and described above, is very compact, sets close to the material, and may be attached to materials of varying thickness without alteration in the length of the fastening-tube d , as more or less of said end will be curled within the recess c , depending upon the thickness of material used, and said curled or burred end is entirely concealed, leaving no unsightly or rough projections when the fastener is attached to the material.

An important feature of our invention is the manner in which the stud-catch is expanded by the setting-tool to conform with the size of the stud member to be used therewith. The upper end of the mandrel upon which the stud-catch is supported is of the exact diameter required to enlarge and hold the stud-catch opening during the setting operation uniformly in all cases and to always insure a perfect fitting of the parts.

We have thus far described this invention as applicable only to a socket member of a glove-fastening; but it will be obvious that the stud member might be formed and secured to the material in the manner shown in Fig. 2. In other words, the stud member if formed slightly extended and similar to the catch A and having the recess c may be secured to the material by a flanged fastening-eyelet having its end curled in the recess at the base in the same manner, in which case the flange of the fastening-eyelet could be flat and the tube very much shorter.

The attaching-rivet D (shown in Figs. 5, 6, 7, and 8) consists of a base-flange d^6 and a hollow shank d , extending therefrom. The end d' of the shank is pointed and is sufficiently sharp to pierce materials with which it is designed to be used. The upper end portion of the shank d' may be provided with a slight annular ridge or offset between the point-section and the body of the shank, and at a suitable place within its length the shank may be perforated, indented, or slotted, as at d^2 , so as to insure the proper upsetting of the rivet and to weaken the shank so that the point d' will not penetrate or injure the stud E.

It will be understood that several perforations, slits, or depressions d^2 may be made in the shank and that they should be irregularly located at different points within the length of the shank, so that the upsetting operation will always thoroughly crinkle the rivet within the stud; but a single perforation or slit has some advantages, because it always insures the bending or turning of the point-section over upon that side of the shank when the upsetting operation takes place.

We also contemplate using a celluloid or other plastic cover for the flange of the eyelet or rivet, and this cover may be attached to the flange by ears or offsets d^4 to anchor the

covering, as shown in Figs. 6 and 8. It will be understood that the covering material is to be applied in a plastic or semiplastic condition and permitted to harden.

Without desiring to limit ourselves to the exact details of the construction shown, what we desire to claim and secure by Letters Patent is—

1. A socket member for glove-fasteners, comprising a catch having a hollow body portion, an outlying base-flange, and an annular recess or contraction at the junction of the body portion and flange, an eyelet having a cap or cover secured thereto, the end of said eyelet being passed through the material and having its tubular edge curled within the annular recess or contraction, substantially as described.

2. The socket member of a glove-fastener consisting of a closed top or cover as b^2 and a flanged fastening-eyelet as B secured thereto, and a stud-catch having a bulging body portion, a recess below the bulge of said body portion to receive the curled end of the fastening-eyelet, and a deflecting-surface integral with the flange of the stud-catch whereby the end of the fastening-eyelet is burred and the socket member is secured to the material substantially as set forth.

3. A stud-catch for glove-fasteners comprising a bulged body portion and outlying base-flange, the body portion being contracted at its junction with the flange to form an annular recess to receive the turned end of a fastening-eyelet, and which also serves as an anvil or clenching-surface for turning the end of the attaching-tube, substantially as described.

4. A stud-catch for glove-fasteners consisting of a catch having a hollow flaring body portion and an outlying base-flange, a groove or recess as c surrounding the said contracted portion and a clenching-surface on said flange.

5. A socket member for glove-fasteners comprising a resilient catch having an outwardly-swelled body portion and an outlying base-flange, a recess at the junction of the body and the flange and an eyelet or fastening set from the opposite side of the material and having its edge curled or clenched within said recess surrounding the catch, said curled portion serving as a guard, shield or stop to limit the expansion of the catch, substantially as described.

6. A stud member of a glove-fastener composed of a hollow head provided with a flange, and a fastener therefor having a hollow piercing-point, a crippling notch or depression in its stem and the exposed surface of its flange covered with celluloid or other plastic material, the stem of the fastener burred within the head of the stud and the flanges of the head and the rivet clamping the material between them.

7. A rivet for securing studs or buttons to imperforate sheet material comprising a base-

flange, a hollow tapering shank rising from said flange, said shank being provided with an acute conical point for piercing the material, substantially as described.

5 8. A rivet for securing studs or buttons to imperforate sheet material consisting of a base-flange, a hollow tapering shank rising therefrom, a conical point at the end of the shank and an annular ridge or offset at the junction of the shank and point, substantially as described.

9. A rivet consisting of a base-flange, a hollow integral tapering shank rising from the center of said flange, a conical point on said 15 shank and a depression or notch at the point of juncture of the shank and point, substantially as described.

10. A hollow rivet comprising a base-flange, an integral tapering shank projected therefrom and a disk of plastic material secured to the outer edge of the flange for covering said flange upon its exposed surface, substantially as described.

11. A hollow rivet comprising a base-flange, 25 a tapering pointed shank rising from said

flange, ears or anchors at the periphery of said flange and a film of plastic material covering the outer surface of the flange and held thereon by said ears or anchors, substantially as described.

30 12. A stud member of a glove-fastener comprising a head having a base-flange, and an annular groove or depression within the flange at the junction of said flange and head portion, substantially as described.

13. A stud member of a glove-fastener consisting of a hollow head having a base-flange, said stud member being secured to the material by a rivet comprising a base-flange, a hollow tapering shank rising from said flange, 40 said shank being provided with an acute conical point for piercing the material, substantially as described.

In testimony whereof we affix our signatures in presence of two witnesses.
